Primary Examiner—A. Hugo Word*Assistant Examiner*—R. Seifert*Attorney, Agent, or Firm*—Leon Gilden**[57] CLAIM**

The ornamental design for a combined dispenser and base, as shown and described.

DESCRIPTION

FIG. 1 is a front elevational view of a combined dispenser and base showing my new design;
FIG. 2 is a rear elevational view thereof;
FIG. 3 is a left side elevational view thereof;
FIG. 4 is a right side elevational view thereof;
FIG. 5 is a top plan view thereof; and,
FIG. 6 is a bottom plan view thereof.
The broken line showing of a bowl is for illustrative purposes only and forms no part of the claimed design.

FIG. 1

FIG. 2

FIG. 3

FIG. 4
